UNITED STATES PATENT OFFICE

2,475,712

GATE VALVE

Walter E. Miller, New Orleans, La.

Application October 26, 1945, Serial No. 624,684

3 Claims. (Cl. 277—33)

1

This invention relates to gate valves, and more particularly to gate valves of the rotary gate type.

A main object of the invention is to provide a novel and improved gate valve structure having locking means for positively maintaining the valve either in its fully opened or fully closed position.

A further object of the invention is to provide an improved gate valve of simple construction which is adapted to be easily and effectively controlled and which is provided with automatic locking means for maintaining the valve elements either in fully opened or fully closed positions.

Further objects and advantages of the invention will appear from the following description and claims, and from the accompanying drawings, wherein:

Figure 1 is a longitudinal cross-sectional view of a valve constructed in accordance with this invention, the valve being shown in fully opened position.

Figure 2 is a cross-sectional view taken on line 2—2 of Figure 1.

Figure 3 is a view similar to Figure 1 but with the valve shown in fully closed position.

Figure 4 is a detail cross-sectional view taken on line 4—4 of Figure 1.

Referring to the drawings, 11 designates the main body portion of the valve, said body portion 11 being formed with hollow flanged arms 12 and 13 for connection to the respective pipe sections between which the valve is interposed, and a central cavity 14. The upper end of body portion 11 is flanged, as shown at 15, and to the top flange 15 is secured a cover member 16 having formed thereon a top yoke element 17. Rotatably supported in top yoke element 17 is a vertical shaft 18, the top of shaft 18 carrying a hand wheel 19 rigidly secured thereto. Shaft 18 is provided with a collar member 20 rigidly pinned thereto which cooperates with hand wheel 19 to maintain shaft 18 in secured relation with respect to yoke element 17, preventing endwise movement of the shaft with respect to the yoke element. Shaft 18 extends downwardly into the valve cavity through a sealing gland member 21 for providing a fluid-tight connection between shaft 18 and cover member 16. The lower end of shaft 18 threadedly engages a vertically movable top abutment member 22 which is formed with a downwardly tapered lower portion 23. Abutment member 22 is generally rectangular in plan.

Secured to abutment member 22 adjacent one end thereof are a pair of depending legs 24, 24, each of said legs being formed with an inwardly projecting cam element 25, said cam element hav-

2

ing a top inclined cam surface 26 and a bottom inclined cam surface 27. Secured to abutment member 22 adjacent the other end thereof are a second pair of depending legs 28, 28 each formed with an inwardly projecting cam element 29 having a top inclined cam surface 30 and a bottom inclined cam surface 31. Secured to the lower ends of legs 24, 24 and 28, 28 is a bottom abutment member 32 formed with an upwardly tapered top portion 33.

Arm 12 is formed with a boss 34 projecting into cavity 14 and formed with straight vertical sides slidably fitting between legs 24, 24. Arm 13 is formed with a similar inwardly projecting boss 35 slidably fitting between legs 28, 28. Boss 34 is formed with a cylindrical seat portion 36 and boss 35 is formed with a similar cylindrical seat portion 37 having the same central axis and curvature as seat portion 36. Rotatively supported on seat portion 36 is a first valve segment 38 and rotatively supported on seat portion 37 is a second valve segment 39, valve segment 39 being formed with a cylindrical center lug 40 which rotatively interfits with a cylindrical center recess 41 formed in valve segment 38. The end surfaces of valve segments 38 and 39 respectively, slidably abut depending legs 24, 24 and 28, 28 whereby said segments are maintained in correct axial positions with respect to seat portions 36 and 37. Each segment is formed with a bore adapted to be aligned in registry with each other and with the seat bores when the segments are in the fully opened position of the valve, as shown in Figure 1.

Valve segment 38 is formed with a pair of upper projections 42 adapted to be abutted by upper cam surfaces 26 of legs 24, 24 to move the segment to its valve opening position responsive to upward movement of legs 24, 24. A pair of lower projections 43 are provided on said segment 38 adapted to be abutted by lower cam surfaces 27 of legs 24, 24 to move the segment to valve closing position responsive to downward movement of legs 24, 24. Valve segment 39 is similarly provided with upper projections 44 adapted to be abutted by cam surfaces 30 to open segment 39 responsive to upward movement of legs 28, 28, and with lower projections 45 adapted to be abutted by cam surfaces 31 to close segment 39 responsive to downward movement of legs 28, 28.

In the open position of the valve segments, top portion 33 of bottom abutment member 32 is adapted to interlock with the bottom radial surfaces of the valve segments to positively maintain the valve open, as shown in Figure 1. In the closed position of the valve, lower portion

23 of top abutment member 22 is adapted to interlock with the top radial surfaces of the valve segments to positively maintain the valve closed, as shown in Figure 3. The valve elements may be moved from the fully opened position shown in Figure 1 to the fully closed position shown in Figure 3, and vice versa, by rotating hand wheel 19 whereby the threaded lower end of shaft 18 moves top abutment member 22 and the parts secured thereto vertically, causing the valve segments to be rotated on their seats.

While a specific embodiment of a gate valve structure has been disclosed in the foregoing description, it will be understood that various modifications within the spirit of the invention 15 may occur to those skilled in the art. Therefore it is intended that no limitations be placed on the invention other than as defined by the scope of the appended claims.

What is claimed is:

1. A gate valve comprising a housing having a pair of connection arms, a pair of cylindrical valve seats in said housing, each valve seat having an opening communicating with a connection arm, a cylindrical valve segment rotatively mounted on each seat, each segment having a bore adapted to register at times with its seat opening, a shaft projecting into said housing, a cam member threadedly engaging said shaft, a second cam member arranged in parallel spaced relation with respect to said first-named cam member, a pair of cam elements arranged in face-to-face relationship interposed between said first and second-named cam members and secured to the latter, means carried by each segment and cooperating with the cam element adjacent thereto for simultaneously rotating the segments on their seats responsive to movement of said cam member axially of said shaft, first means carried by said second cam member interlocking with said segments when said segments have been rotated to valve opening position, and second means car-

ried by said first-named cam member interlocking with said segments when the segments have been rotated to valve closing position.

2. The structure of claim 1, and wherein the 5 valve seats are arranged along a common axis with the valve segments interposed between said seats and each segment mounted for rotation about an axis at a right angle with respect to the axis of said seats and wherein the end surface of one of said valve segments opposite to its seat-engaging surface is provided with a cylindrical lug and the end surface of the other of said valve segments adjacent to the end surface of said one segment having the cylindrical lug is provided with a cylindrical recess, said cylindrical lug interfitting said cylindrical recess to thereby rotatably inter-lock the valve segments for rotation about their right-angle axes with respect to the common axis of said valve seats to the axis of said cylindrical surface.

3. The structure of claim 1, and wherein the 10 valve segments are interposed between said seats and each mounted for rotation about an axis at the right angle with respect to the axis of said seats with the opposed side surfaces of said segments slidably abutting said cam elements.

WALTER E. MILLER.
